AUTOMATIC RETURN DEVICE FOR CONTROL MEMBERS

Friedrich Freitag, Wallstadt, Germany, assignor
to Zellstofffabrik Waldhof, Mannheim-Waldhof, Germany, a joint-stock company of Germany

Application February 3, 1938, Serial No. 188,591
In Germany March 28, 1936

1 Claim. (Cl. 74—501)

This application corresponds to the application of Zellstofffabrik Waldhof, Serial No. Z.23108, which was filed in Germany on 28th March, 1936.

For allowing starters or control switches for electric motors and the like devices (for example, valves in gas and liquid conveying conduits and the like), which are adapted to be moved in either direction out of a zero position by means of two oppositely acting pull members to return automatically into the zero position again on releasing the pull members, spiral leaf springs have generally been employed. In this case two springs are necessary, namely a spring for the return of the starter from each direction, the tension produced in said spring by the pulling being liberated on release and the apparatus being automatically returned into its centre position.

Automatic return by means of spiral springs has, however, considerable disadvantages. The springs which are encased in a housing are not easily accessible, are troublesome to clean, foul and stick easily and require frequent repairs, while fracture of the springs is comparatively frequent, the entire apparatus being thereby put out of operation.

According to the invention, these disadvantages are obviated and a satisfactory return of the device into the central position and hence a reliable and undisturbed operation of the apparatuses may be ensured by arranging on each pull member a weight which is raised upon a pull being exerted on the opposite member, and upon release returns into the stationary inoperative position.

If the apparatus is in its central position, the two weights also occupy their inoperative positions by resting for example on a stationary support or being suspended from a stationary device. In order that the weights will be able to move up and down within certain limits defined by lifters or the like mounted on the pull members, each of said weights is provided with a preferably central bore, through which the pull member passes. In order to ensure satisfactory sliding of the weights, it is expedient to allow them to run in guides, for example on vertical rails or in tubes.

A construction of the invention is shown by way of example in the accompanying figure.

At A is shown the starting pulley of an electric motor. By exerting a pull on one of the cables or chains B₁ and B₂, the pulley can be rotated to the left or to the right out of the zero position, a motor being thereby switched for lifting or lowering. For example, if the chain B₁ is pulled, the chain B₂ passing through the bore G₂ is raised and its lifter C₂ carries the weight D₂ with it, the latter being guided in a tube E₂. Instead of external guide tubes E₂, guide rails or internal guide tubes may be used. Upon releasing B₁, the weight B₂ by bearing on the lifter C₂ presses the chain B₂ downwardly until it has returned into its inoperative position F₂. The starting pulley A is thereby turned back and the starter returns to its zero position. Further running down of the chain B₂ is prevented by abutment of the lifter C₁ of the chain B₁ against the weight D₁ which has remained in the inoperative position F₁.

Upon pulling the chain B₂, the same cycle occurs in respect of the weight D₁ moving in the guide E₁ and provided with a bore G₁.

I claim:

In mechanism for effecting return to a neutral position of a control device displaceable in either direction from such position, the combination with a pulley operatively connected to the control device, a flexible member passing over said pulley and having generally vertical runs, an abutment connected to each of said runs, a weight supported for engagement by each of said abutments, each of said weights being positioned for engagement by the associated abutment on initiation of movement of the flexible member in a direction to raise such abutment and the weight engaged thereby, whereby on release of the flexible member, the weight thus raised will return the flexible member and the pulley to the initial position thereof, and stationary means cooperating with each of said weights to guide the latter in the direction of the associated runs of said flexible member.

FRIEDRICH FREITAG.
